M. C. STERN.

ROLL PAPER ATTACHMENT FOR TYPE WRITERS.

APPLICATION FILED DEC. 12, 1913.

1,101,581.

Patented June 30, 1914.

UNITED STATES PATENT OFFICE.

MILTON C. STERN, OF DAYTON, OHIO, ASSIGNOR TO THE EGRY REGISTER COMPANY, OF DAYTON, OHIO, A CORPORATION OF OHIO.

ROLL-PAPER ATTACHMENT FOR TYPE-WRITERS.

1,101,581.

Specification of Letters Patent. Patented June 30, 1914.

Application filed December 12, 1913. Serial No. 806,163.

To all whom it may concern:

Be it known that I, MILTON C. STERN, a citizen of the United States, and a resident of the city of Dayton, in the county of 5 Montgomery and State of Ohio, have invented certain new and useful Improvements in Roll-Paper Attachments for Type-Writers, of which the following is a full, clear, and exact description, reference being 10 had to the accompanying drawings, forming part of this specification.

My invention relates to attachments for typewriting machines designed to hold and supply the paper for the type printing 15 mechanism, in continuous rolls, and in which provision is made for making manifold copies by means of supplemental inking ribbons.

The several features of my invention and 20 the various advantages resulting from their use conjointly or otherwise will be apparent from the following description and claims.

In the drawings, Figure 1 is a side elevation of a typewriting machine, with my improvements applied thereto. Fig. 2 is a 25 rear elevation of the typewriter, with the attachment applied. Fig. 3 is a detailed view, in perspective, showing the means for supporting and the tension device for the 30 paper roll. Fig. 4 is a plan view of the same.

My improvements may be applied to any of the well known constructions of typewriting machines for visible writing, but the particular construction of typewriter 35 with which I have chosen to illustrate my improvements is the typewriter known as the Underwood, in which the framework of the machine is indicated by 1, the keys by 2, with the impression cylinder or platen 3 mounted in a carriage 4, which is arranged 40 to be shifted by the operation of the space key to carry the paper from side to side as the writing progresses. In this form of machine, the inking ribbon 5 is mounted on two 45 horizontally disposed spools, one of which is shown at 6 in Fig. 1, which spools are suitably journaled one on one side and the other on the other side of the central portion of the machine, with the ink ribbon carried in 50 front of the impression cylinder or platen, and between which and the ribbon the paper to be written on is passed to receive the impression from the type selected by the keys operated. For the purpose of advancing 55 the paper for line spacing, the impression

cylinder or platen over which the paper is carried, is rotated by means of the line space lever 7, pivoted at one side of the carriage frame.

My improved attachment for such a typewriter consists in the construction for holding the various rolls of paper from which webs are to be furnished for the printing. A metal framework is provided for this purpose, comprising vertical side standards 60 8, 9, with cross bars 10 at the top and at the bottom 12.

The lower portion of the frame is supported in such a manner as to hold the same against movement toward or away from the typewriter, but to permit the frame to move freely in the direction of movement of the paper carriage of the typewriter. This may be accomplished in various manners, and, in the present instance, I have shown the 70 bottom 12 as provided with journal bearings for the spindles of a pair of grooved carrying wheels 13, 14, by means of which the frame is supported on the track 15 to be carried from side to side, with the reciprocal movement of the carriage of the typewriter, and to which the frame is secured, as will be hereinafter described. At suitable points on the uprights 8, 9 of the roll paper frame, angle plates 16, 16 are secured, which are 75 formed with supports 18 (see Fig. 3) for the reception and support of the spindles of the rolls of paper, so that the rolls of paper 19, 20, 21 and 22 can be readily and easily mounted in the frame to rotate freely as the 80 several webs of paper are drawn from the rolls. On the end of the paper rolls in which the spindles are supported in the plate 16, the rolls are preferably provided with disk washers 23, to prevent the paper 85 from coming in contact with the standard, while on the opposite end the disks are omitted, and a tension device is provided to bear against the end of each roll of paper to maintain proper tension on the paper. 90

Pivotedly mounted on the rod 24, secured parallel with and at the side of the upright 8 are Z-shaped spring plates 25, one for each roll of paper, with the outer section 26 of each plate arranged to bear against the 95 end of its respective roll of paper, and with the tension maintained by coiled springs 27 mounted on the rod 24 above and below the plate and bearing thereon. In mounting the rolls of paper, these tension 100

105

110

plates are easily swung away from the rolls as shown in Figs. 3 and 4. The track 15 upon which the paper roll frame rides is properly supported at the bottom and rear 5 of the typewriter frame by the brackets 29, which brackets are supported and rigidly secured to the main framework at 30, 30, by screws or otherwise; while the roll paper frame is held in vertical position to be 10 moved from side to side with the movement of the typewriter carriage by arms 31, 31, which are pivotally secured to the carriage attachment and at the outer ends are hooked over studs on the roll paper frame at 32, 32. 15. From the foregoing description, it will be evident that the roll paper frame may be readily and easily secured to the typewriting machine without interfering with or altering the machine structure in any way, 20 and also that the rolls of paper may be mounted on the frame with equal ease and convenience.

To load the machine, the paper rolls are first mounted in the roll frame as heretofore described, and the paper webs 91, 92, 25 93 and 94 are passed over the guide rods 95, which are mounted on standards 96 on the arms 31 which brace the roll frame in position. The paper webs are then passed 30 under and partially around the impression roller, the web 91 in contact with this roller, with the strips of inking ribbon interposed between the sheets. To finally insure against the falling and curling of the paper 35 from the rolls before it passes over the guide rods, I provide the tongue member 97. This tongue member is made of suitable material such as spring metal, is attached to the cross bar 10, and bears against 40 the webs 91 and 92 from the top rolls. This is all that is needed, as the lower rolls take care of themselves. The device is thus secure from paper falling forward after the 45 end has passed through the platen. The tongue will also prevent unrolling of the paper on the rolls.

The complete detachability of the attachment is a very important feature. Most standard typewriter carriages will serve as 50 a mounting for it, as it is back out of the way of working parts. Such alterations as

spacing the side pieces 8 and 9 farther apart for wide carriages amount to practically no change. This simple means of mounting a plurality of rolls could be adapted to many 55 kinds of machines and in the use of words "typewriting machine" in this specification, kindred and allied machinery is intended to be covered as well.

Having thus described my invention, what I claim as new and desire to secure by Letters Patent, is:—

1. In a manifolding attachment for typewriting machines, a frame for carrying a number of rolls of paper comprising upright bars, bearing plates on said bars for the rolls of paper, upright rods parallel to the bars, and tension devices for the rolls of paper mounted on the rods and between them and the bars. 65

2. In a manifolding attachment for typewriting machines, a frame for carrying a number of rolls of paper comprising upright bars, bearing plates on said bars for the rolls of paper, upright rods parallel to the bars, and tension devices for the rolls of paper mounted on the rods and bearing on the bars. 70

3. In a manifolding attachment for typewriting machines, a frame for carrying a 80 number of rolls of paper comprising upright bars, bearing plates on said bars for the rolls of paper, upright rods parallel to the bars and spring plates having flat portions for contacting with the rolls, and 85 mounted on the rods and extending between them and the bars so as to bear on the bars.

4. In a manifolding attachment for typewriting machines, a frame for carrying a 90 number of rolls of paper comprising upright bars, bearing plates on said bars for the rolls of paper, upright rods parallel to the bars, and tension devices for the rolls of paper mounted on the rods and between 95 them and the bars, said frame having a cross bar at the top and tension means for the sheets of paper after they leave the rolls.

MILTON C. STERN.
